UNITED STATES PATENT OFFICE.

PERCY W. MARTIN, OF BAY CITY, MICHIGAN, ASSIGNOR TO SMALLEY GENERAL CO., OF BAY CITY, MICHIGAN, A CORPORATION OF MICHIGAN.

METHOD OF MAKING SCREW-CUTTING DIES AND THE LIKE.

Application filed October 21, 1920. Serial No. 418,371.

To all whom it may concern:

Be it known that I, PERCY W. MARTIN, a citizen of the United States, residing at Bay City, in the county of Bay and State 5 of Michigan, have invented certain new and useful Improvements in Methods of Making Screw-Cutting Dies and the like; and I do hereby declare the following to be a full, clear, and exact description of the invention, such as will enable others skilled in the art to which it appertains to make and use the same.

This invention relates to a method for forming screw-cutting dies or "chasers" and 15 pertains more particularly to a method whereby I am enabled to form at one operation a plurality of sets of screw-cutting dies, each die of any one of said sets of dies being interchangeable with the corresponding die 20 of any other set.

With the foregoing and certain other objects in view which will appear later in the specification, my invention consists in the method herein described and claimed and the 25 equivalents thereof.

Heretofore chasers for dies of two and one-half inch diameter and larger have been formed by milling. Smaller diameters have not usually been milled because the milling 30 hob had to be so small that it did not possess the proper strength and rigidity.

If the chasers intended for a die of small diameter were attempted to be milled by arranging them at the quarter points of a 35 larger diameter circle and then milling with a hob of the correct pitch, sets of dies of the correct pitch would be obtained, but the helical angle would be incorrect.

Therefore, to produce a correct set of dies 40 for small diameter work by milling the dies while arranged on a circle of larger diameter, it is necessary to employ the step in my method which consists in imparting to the hob a sufficiently increased movement 45 of lead to produce the correct helical angle on the dies, as will be later described.

My invention applies the method of milling 50 to the forming of screw-cutting dies adapted to small diameter work and it also enables several such sets of dies to be threaded at one operation, by a milling cutter which is of large diameter, even larger than the diameter of the work.

The fundamental requirement for an accurate set of screw-cutting dies is that the 55 die threads shall have the proper pitch, the proper lead and the proper helical angle, and that the cutting die shall have the proper clearance or "back-off." My improved method produces dies possessing all 60 of these qualities.

In carrying out my method, I employ the usual face-plate and lead-screw mechanism of the ordinary milling machine or screw-cutting lathe, or an equivalent machine, as 65 the case may be.

I take several sets of die blanks and arrange them on a face-plate in circular arrangement, the diameter of the circle of cut being several times larger than the diameter 70 of the "work."

I cut the die teeth by means of the usual multiple thread milling hob or cutter.

In the drawings, Fig. 1 is a diagrammatic front view of the face-plate of a die-threading machine, showing a plurality of sets of die blanks in place and also showing the cutting hob for forming the die teeth. 75

Fig. 2 is a part sectional view, taken on the line 2-2 of Fig. 1. 80

Fig. 3 is a tabulation showing the dimensions of iron pipes of various sizes and the required diameter of cutting circle and the required lead.

Fig. 4 is a diagrammatic view, not to 85 scale, showing the means of determining the amount of "lead" movement required to be given to the hob in order that each resulting set of dies may when assembled produce on small diameter work a thread having the required standard pitch. 90

Fig. 5 is a diagrammatic view showing the work being threaded by a die, formed by my improved method, and showing the relief or "backing-off" clearance imparted to 95 the finished die.

As is clearly shown in the drawings, my method may be carried out by employing the usual face-plate 1 and the cutting may be done by the usual multiple toothed hob 100 2, the face-plate and hob driven in the usual manner. The hob is adapted to be given an axial movement of lead, by means of a lead screw or other device well-known in the art and consequently not shown in the 105 drawings.

I form the cutting teeth on the dies 3 by the following method.

If the size of pipe to be threaded, as indicated diagrammatically at W, Fig. 5, is 5 for example, one-half inch, and the pitch of the finished standard pipe thread 5 is, say, fourteen threads to the inch, the outside diameter of the pipe is .840 inch.

Assuming now that I desire to make four 10 sets of these small diameter dies at one operation of the milling machine, I divide the circle of the face-plate—see Fig. 1—into four quarters and arrange the four die blanks of a set, equally spaced, one set in 15 each quarter, as shown at R, S, T, U. The diameter of this cutting circle must bear a predetermined relation to the diameter of the work which in the assumed case is one-half inch. I, therefore, find the proper diameter 20 of the milling circle by multiplying the diameter of the work, in the case illustrated .840 inch, by the number of sets of dies arranged on the circle, viz four. Hence .840 inch times 4 equals 3.36 inch, which is the 25 proper diameter of the milling circle.

The pitch of a standard one-half inch pipe thread is fourteen threads to the inch. The pitch of the teeth of the milling cutter is made fourteen to the inch, but the "lead" 30 or axial movement imparted to the milling hob during one revolution of the face-plate must be four times one-fourteenth or two-sevenths inch, corresponding to three and one-half pitch, as shown by the table, Fig. 35 3, and by the diagram, Fig. 4.

That part of the base of the triangle marked $\frac{1}{4}$ rev. equals the circumference of the work and the vertical line P equals the pitch of the thread. The diagonal line represents 40 the developed thread and the angle between this line and the base line is the helical angle.

By extending the base line to make its length equal four times the circumference 45 of the work or 1 rev., and extending the diagonal line and projecting a vertical line from the end of the base line until it intersects the diagonal, the length 4P of the vertical line will equal four times the pitch P.

50 Therefore, to mill four sets of small diameter dies R, S, T, U on a large diameter circle it is necessary to impart to the hob or milling cutter a lead equal to four times the pitch. The actual lead movement of the hob in cutting each set of dies, as in Fig. 1, will then be exactly equal to the pitch.

All four sets of cutting dies are threaded during one revolution of the face-plate. The helical angle of the threads so formed 60 on each set of dies R, S, T, U is exactly the same as if the four dies of each set had been arranged in a small circle equal in diameter to the diameter of the work, and then tapped by a standard fourteen pitch 65 tap. Thus, by arranging a plurality of sets

of dies, as four sets, on the face-plate and by employing a hob of fourteen pitch and by giving the hob a lead movement equal to four times the pitch, I produce at one operation four sets of screw-cutting dies, 70 each of which has the proper standard lead, pitch, helical angle and clearance.

Referring to Fig. 5, $\frac{D}{2}$ represents the radius of the pipe or work to be threaded. 75 3 is the cutting die, 4 the die tooth, 5 the depth of the thread in the work and $\frac{A}{2}$ is the radius of the milling circle. Therefore, 80 the distance C represents the clearance at the top of the thread, that is, the amount the die 3 is relieved or "backed off" when the die is used to cut a pipe of diameter W.

Although a plurality of sets, as R, S, T, U 85 may be made at one operation by the herein described method, it is also frequently desirable that on the next operation of the machine the resulting sets may be exact duplicates of the first sets. To accomplish this result and to produce an indefinite number 90 of interchangeable sets it is only necessary to start the cutting hob in each case on the corresponding cutter, as for example, the first cutter of set R, as shown in Fig. 1, and to insure that at each operation the position 95 of the hob longitudinally with respect to the said die is the same. This can easily be accomplished by inserting a shim between the end of the hob and the face-plate, as at 6 in Fig. 2, so that at the commencement of 100 each successive operation the longitudinal position of the hob will be identical with respect to the position of the first die of the set.

While I have shown and described a certain type of face-plate and hob for forming screw-cutting dies, it will be understood that any other type of machine might be employed for this purpose. My improved 105 method is not dependent upon the employment of any certain type of machine.

For purpose of illustration and explanation I have described a face plate spaced to accommodate four sets of dies. It will be understood, however, that one of these four 115 sets, or more than one, might be omitted from its assigned space without interfering with the correct cutting of the remaining sets and without departing from my invention as set forth in the claims.

It will also be noticed that I have described one set of dies, as R, S, T, U, each set consisting of four cutters, but it will be observed that if desired the first two cutters of, say, set S, could be mounted in the space 125 allotted to that set and the last two cutters of set S could be mounted in the third and fourth positions of set R and the four cutters thus formed would comprise a complete set.

Similarly any other suitable or desirable 130

arrangement or division of the sets of cutters may be made without departing from my invention as set forth in the claims.

Having thus described my invention, what 5 I claim and desire to secure by Letters Patent is:

1. The herein described method of forming at one operation a plurality of sets of screw-cutting dies adapted to cut work 10 of small diameter, said method comprising arranging a plurality of sets of die blanks on a milling circle as many times the diameter of the work upon which the dies are to be used as there are sets of dies, forming 15 teeth on said blanks by milling, and simultaneously imparting to the milling cutter and work a relative longitudinal movement such that the milling cutter during one revolution of the work mills a thread having a 20 lead as many times the pitch of a set of dies as there are sets of dies.

2. The herein described method of forming at one operation a plurality of sets of screw cutting dies comprising arranging a 25 plurality of sets of die blanks in circular form on a milling circle as many times the diameter of the work upon which the dies

are to be used as there are sets of dies, forming teeth on said blanks by milling and simultaneously imparting to the milling cutter a movement of lead as many times the pitch of a set of dies as there are sets of dies, whereby to produce in the work a thread having the required helix angle.

3. The herein described method of forming at one operation a plurality of sets of screw cutting dies adapted to cut work of small diameter, said method comprising arranging spaces for a plurality of sets of die blanks on a milling circle as many times the 40 diameter of work upon which the dies are to be used as there are spaces for sets of die blanks, placing die blanks in one or more of said spaces, forming teeth on said blanks by milling, and simultaneously imparting to the 45 milling cutter and work a relative longitudinal movement such that the milling cutter during one revolution of the work mills a thread having a lead as many times the pitch of a set of dies as there are spaces for sets 50 of dies.

In testimony whereof, I affix my signature.

PERCY W. MARTIN.
